UNITED STATES PATENT OFFICE.

NATHAN L. BURTON, OF GALESBURG, ILLINOIS.

SUPPORTING DEVICE FOR LADIES' HAIR.

1,240,307.

Specification of Letters Patent. Patented Sept. 18, 1917.

Application filed January 18, 1917. Serial No. 143,126.

To all whom it may concern:

Be it known that I, NATHAN L. BURTON, a citizen of the United States, residing at Galesburg, in the county of Knox and State 5 of Illinois, have invented certain new and useful Improvements in Supporting Devices for Ladies' Hair, of which the following is a specification.

This invention relates to supporting devices for ladies' hair.

The object of the invention is to provide a simply constructed cheap device of this character which will effectively support ladies' hair when in unconfined loose condition and hold it away from her shoulders to permit the air to circulate freely around and through it and prevent wetting of the shoulders when the hair has been shampooed and during the drying thereof.

With the foregoing and other objects in view, which will appear as the description proceeds, the invention resides in the combination and arrangement of parts and in the details of construction hereinafter described 25 and claimed, it being understood that changes in the precise embodiment of the invention herein disclosed may be made within the scope of what is claimed without departing from the spirit of the invention.

In the accompanying drawings:

Figure 1 represents a side elevation of this improved support shown applied,

Fig. 2 is a perspective view of one form of the support detached,

Fig. 3 is a similar view showing another form thereof.

In the embodiment illustrated in Figs. 1 and 2 this improved hair supporting device is shown constructed from a single piece of 40 heavy wire which may be plated or not as desired and which is bent midway its ends to form a substantially circular open loop 1 adapted to encircle the rear portion of the neck of the user adjacent the shoulders as 45 is shown clearly in Fig. 1, feet 2 are formed at the free ends of said loop and rest on the shoulders and merge into upstanding arms 3 which curve laterally in a direction toward the closed portion of the loop 1, and 50 have their free ends extended laterally toward each other in overlapping relation to form a hair rest 4. The terminals of these overlapping ends are bent to form eyes 5, the eye 5 on one arm being slidably engaged 55 with the other arm to adapt the device to

be adjusted to vary the length of the hair rest 4.

In the form shown in Fig. 3 the shoulder and neck engaging portion thereof is the same as that shown in Fig. 2 being constructed of a single piece of wire, the free ends of the arms 3 of which are bent to form eyes 5' which are engaged with a rod 6, said rod forming the hair rest in this case. By sliding the eyes 5' on the rod 6 the 65 arms 3 may be positioned closer together or farther apart to suit the comfort of the user.

In the use of this supporter the loop 1 encircles the back portion of the neck as shown in Fig. 1 and the upstanding arms 3 70 position the hair rest 4 of Fig. 2, and 6 of Fig. 3 under the hair adjacent the head, the position of said rest relative to the head being controlled by the curvature of the arms 3. The weight of the hair resting on 75 the support serves to hold it securely in position on the shoulders of the user and thereby prevents the wet hair from contact with the clothes and shoulders of the wearer, and permits the air to circulate through and 80 around the hair to facilitate the drying operation.

From the foregoing description, taken in connection with the accompanying drawing, the advantages of the construction and of 85 the method of operation will be readily apparent to those skilled in the art to which the invention appertains and while I have described the principle of operation of the invention together with the device which I 90 now consider to be the best embodiment thereof, I desire to have it understood that the device shown is merely illustrative and that such changes may be made as are within the scope of the claimed invention.

I claim:

1. A device of the class described comprising a support for engaging the neck of the wearer having upstanding arms rising therefrom, and a hair rest connecting the 100 ends of said arms, said arms being adjustable toward and away from each other.

2. A device of the class described comprising a loop-shaped support for encircling the neck of the wearer and having rearwardly curved upstanding arms with a hair rest carried by said arms, and shoulder engaging feet formed at the junction of said arms with said loop-shaped support.

3. A device of the class described com-

prising a loop-shaped support for encircling the neck of the wearer and having rearwardly curved upstanding arms rising therefrom, and a hair rest connecting the 5 ends of said arms, said arms being adjustable toward and away from each other.

4. A device of the class described comprising a loop-shaped support for encircling the neck of the wearer and having rearwardly curved upstanding arms rising 10 therefrom, and a hair rest connecting the 5 ends of said arms, said arms being adjustable toward and away from each other.

ends of said arms, said arms having eyes at their free ends slidably engaging said hair rest to provide for the adjustment of the arms toward and away from each other. 15

In testimony whereof I affix my signature in presence of two witnesses.

NATHAN L. BURTON.
